UNITED STATES PATENT OFFICE.

FRITZ BALZER, OF MOLINE, ILLINOIS, ASSIGNOR TO TROY LAUNDRY MACHINERY CO., LTD., OF CHICAGO, ILLINOIS, A CORPORATION OF NEW YORK.

WASHING MACHINE.

Application filed February 5, 1923. Serial No. 616,875.

To all whom it may concern:

Be it known that I, FRITZ BALZER, a citizen of the United States, residing at Moline, in the county of Rock Island and State of Illinois, have invented certain new and useful Improvements in Washing Machines, of which the following is a specification.

The present invention relates to washing machines.

10 More particularly the present invention relates to washing machines of the cylindrical type in which a cylindrical drum revolves within a casing, the inner walls of which casing conform to the outline of said cylindrical drum. As commonly manufactured, the cylindrical drum is provided with at least one swinging door hinged about an axis parallel with the axis of said drum. As heretofore manufactured, a considerable 15 amount of space is wasted in the annular space between said cylindrical drum and its outer casing for the reason that a relatively large amount of clearance has been required to accommodate the fittings for said door. 20 As a consequence of this wastage of space there has been an accompanying wastage of water, fuel, soap and such washing chemicals as have been used in the washing machine.

25 An object of the present invention is to provide a washer of the cylindrical type in which the rotating cylinder or drum may fit within the outer casing with relatively small clearance.

30 A further object is to provide a washing machine in which the clearance between the rotating cylinder or drum and the enclosing casing is reduced to a minimum and in which the danger of escape of articles from 35 within the drum is minimized.

A further object is to provide a construction of rotating cylinder or drum which is sturdy, which has no protruding parts beyond the cylindrical outline of said drum, and which will reduce to a minimum the 40 danger of escape of garments from said drum.

45 A further object is to provide a rotary cylinder or drum having a swinging door, which provides sturdiness in a structure in which the trimmings for said door lie within the general outline of the drum.

Further objects will appear as the description proceeds.

Referring to the drawings—

55 Figure 1 is a view in elevation of a drum employing the principles of the present invention, a door for said drum being illustrated;

Figure 2 is a view, on an enlarged scale, 60 showing the end portion of the door and the drum of which said door forms a part;

Figure 3 is a sectional view taken along the plane indicated by the line 3—3 of Figure 2;

Figure 4 is a sectional view taken along the plane indicated by the line 4—4 of Figure 2; and

Figure 5 is a sectional view taken along the line 5—5 of Figure 3.

70 The numeral 1 indicates a drum mounted within the casing and provided with the staves 2—2, which staves are securely mounted in suitable end heads, said staves being held in place by means of the circumferential bands 3—3 located at the ends of the drum. Hinged about the axis A—A is the door 4, which door extends to the line marked B—B in Figure 1. According to common practice, the staves 2—2 may be 75 spaced slightly apart and the staves may also be provided with holes to permit the circulation of washing medium. The door 4 substantially fills the space between the circumferential bands 3—3.

80 The door 4 is recessed or sunk below the cylindrical contour of the drum, so that all trimmings necessary for the opening and closing of the door and the holding of the door in closed position are within the cylindrical boundaries of the circumferential bands 3—3 at each end of the cylinder.

85 The door 4 is provided at each of its ends with a hinge 5, each of which hinges consists of two main pieces. The butt end of each hinge is indicated by the numeral 6 and is rigidly fastened to the hinge rib 7, which hinge rib is one of the staves of the cylinder but is ordinarily heavier than adjacent staves. The butt end 6 is secured 90 to the hinge rib 7 by means of bolts 8—8 and wood screws 9, the butt end 6 being sunk into the hinge 7 whereby to avoid any projections beyond the general cylindrical

boundary of the cylinder. The construction provides a rigid support for the butt ends 6 of the hinges 5-5. The swinging portion 10 of each of the hinges 5-5 is fastened to the butt end 6 by means of a bolt or pin 11. Each of the bolts 11 may be rivet-shaped, the end opposite the head being split whereby the two halves may be spread apart to perform riveting functions. 10 This type of bolt or pin for providing a pivot for the door 4 has been found useful in practice, inasmuch as repairs when necessary may be readily accomplished.

The door 4 is made up of a plurality of staves 12-12, the swinging portion 10 of each hinge being fastened to each of the staves 12-12 by means of bolts 13-13. The stave 12 which is distant from the hinge rib 7 is ordinarily termed a latch stave 20 and in conventional designs of washers as heretofore commonly used, this latch stave has been cut out at each of its ends to receive the receptacle for the latch. This construction has added to the cost of manufacture and has involved the weakening of the woodwork of the cylinder. According to the present invention, the manufacturing cost is reduced and weakening of the woodwork is avoided. According to the 30 construction of the present invention, the member 10 of each hinge is provided with a pair of upstanding guides 14-14 which provide grooves for slidably holding the latch bolt 15. Said member 10 is also provided 35 with the bridge portion 16 which overlies the latch bolt 15 in order to hold said latch bolt against movement outwardly in a diametrical direction with reference to the washing cylinder. The bridge portion 16 may be secured to the member 10 of the hinge by means of bolts 16'-16'. The latch bolt 15 is cut out for the reception of the spring 17, one end of which rests on the front portion of the latch bolt 15, the other 40 end of said spring resting against a projection 18 which is rigid with the member 10 of the hinge. Said latch bolt has a finger piece 19 by means of which said latch bolt may be conveniently manipulated.

45 The under side of the door 4 may be provided with the metal strengthening member 20 for preventing the bolt heads from being pulled into the wooden staves after said staves have been subjected to use.

50 The front portion of each latch bolt 15 enters into the head section of the cylinder. For the purpose of receiving said latch bolt, each head section is provided with a pocket 20', each latch bolt being adapted to underlie one of the circumferential bands 3-3. Inasmuch as there is considerable wear due 55 to the movement of the latch bolt, an auxiliary wear piece 21 is provided, which is located on the inner side of each circumferential band 3 in a position to engage its

corresponding latch bolt 15. Preferably said wear piece 21 should be of symmetrical construction so that it may be turned end for end when one side shows the effect of wear. Said wear pieces 21-21 may be secured in 70 place by the screws 22-22 whereby said wear piece may be conveniently removed when wear has occurred and reversed in position whereby to present an unworn portion for an abutment against which the 75 latch bolt 15 may engage.

The swinging door 4 engages the rib 23, which may be stepped in its formation as indicated in Figure 3. The stepped portion of rib 23 may be provided with a Z-shaped metal protecting means 24. The lower shelf 25 of the member 24 is engaged by the under side of the door 4 and prevents small articles from working their way out of the washing machine. Not only does the member 24 provide a close fitting abutment for the swinging door 4, but it also effectually resists wear, which is an important feature in the art to which the present invention pertains, inasmuch as the construction is in 90 service subjected to heavy duty.

95 Mounted on the inside of each cylinder head at the portion of the periphery of the cylinder in proximity to the door 4 is a wood strip 26, which follows the cross sectional contour of the door. As shown in Figure 5, the door engages said strip 26 to prevent the egress of small articles between the door and the cylinder head.

100 The present invention permits a substantial and heavy rib and latch assembly for cylinders of washing machines without necessitating a large clearance between the rotating cylinder and the outer casing. The cylinder may have as small clearance as is practicable from a mechanical standpoint, thereby accomplishing a considerable saving in water, soap and other washing chemicals. When it is considered that the clearance which is necessary in former types of 105 washing machines occurs beyond the periphery of the cylinder, it will be realized how considerable is the volume of the space saved by the present invention. The consequent saving in washing materials is therefore a very important item to the laundry owner.

110 Though a preferred embodiment of the present invention has been described in detail, many modifications will occur to those skilled in the art. It is intended in this patent to cover all such modifications that fall within the scope of the invention as defined by the appended claims.

115 What is claimed is:

120 1. A washing cylinder comprising a cylindrical portion having a swinging door hinged about an axis parallel with the axis of said cylindrical portion, said swinging door being sunk below the peripheral sur-

face of the remainder of said cylindrical portion, said swinging door being provided with a hinge and a latch portion, both located within the peripheral contour of said 5 cylindrical portion.

2. A washing cylinder comprising a cylindrical portion having a swinging door hinged about an axis parallel with the axis of said cylindrical portion, said swinging 10 door being sunk below the peripheral surface of the remainder of said cylindrical portion, said swinging door being provided with a hinge and a latch portion, both located within the peripheral contour of said 15 cylindrical portion, said cylindrical portion being provided with circumferential end bands, said latch member being provided with a latch bolt adapted to underlie one of said circumferential bands for locking 20 purposes.

3. A washing cylinder comprising a cylindrical portion having a swinging door hinged about an axis parallel with the axis of said cylindrical portion, said swinging 25 door being sunk below the peripheral surface of the remainder of said cylindrical portion, said swinging door being provided with a hinge and a latch portion, both located within the peripheral contour of said 30 cylindrical portion, said cylindrical portion being provided with circumferential end bands, said latch member being provided with a latch bolt adapted to underlie one of said circumferential bands for locking 35 purposes, said circumferential band being provided with a reversible wear plate for engagement with said latch bolt.

4. In a washing machine, a cylindrical drum having circumferential end bands and 40 a swinging door hinged about an axis parallel with the axis of said drum, said door being sunk below the peripheral contour of said drum, a hinge for said door, said hinge being provided with a latch member provided with a latch bolt and a guide member therefor, said hinge and latch mechanism all being located within the circumferential 45 contour of said drum, said latch member being adapted to underlie one of said circumferential bands for holding functions, said guide member for said latch bolt being bolted to said hinge member whereby to be 50 readily replaceable in the event of wear.

5. In a washing machine, a casing, a rotary cylinder mounted within said casing and having small clearance relative thereto, said cylinder having a swinging door hinged about an axis parallel with the axis of said cylinder, said door being sunk below 55 the circumferential contour of said cylinder and being provided with hinge and latch trimmings located within said circumferential contour, said latch trimmings being mounted upon said hinge trimmings.

6. In a washing machine, a casing, a ro-

tary cylinder mounted within said casing and having small clearance relative thereto, said cylinder having a swinging door hinged about an axis parallel with the axis of said cylinder, said door being sunk below the 70 circumferential contour of said cylinder and being provided with hinge and latch trimmings located within said circumferential contour, said latch trimmings being mounted upon said hinge trimmings, said cylinder 75 having circumferential end bands, said latch trimmings being adapted to underlie said circumferential end bands for latching purposes.

7. In a washing machine, a casing, a rotary cylinder mounted within said casing and having small clearance relative thereto, said cylinder having a swinging door hinged about an axis parallel with the axis of said cylinder, said door being sunk below the 80 circumferential contour of said cylinder and being provided with hinge and latch trimmings located within said circumferential contour, said latch trimmings being mounted upon said hinge trimmings, said cylinder 85 having circumferential end bands, said latch trimmings being adapted to underlie said circumferential end bands for latching purposes, said circumferential end bands being provided with reversible wear plates for engagement with said latch trimmings.

8. In a washing machine, a casing, a rotary cylinder mounted within said casing and having small clearance relative thereto, said cylinder having a swinging door hinged about an axis parallel to the axis of said cylinder, said door being sunk below the circumferential contour of said cylinder, longitudinally extending staves for supporting the longitudinal edges of said door, one 100 of said staves constituting the hinge support of said swinging door, the other of said staves constituting an abutment for the swinging edge of said door, said latter mentioned stave being of stepped conformation 105 to permit close fitting of the door when in closed position.

9. In a washing machine, a rotary cylinder, said cylinder having an outwardly swinging door hinged about an axis parallel with the axis of said cylinder, said door being sunk below the circumferential contour of said cylinder, said door being provided with hinge and latch trimmings located within said circumferential contour, the ends of said cylinder being provided with projections engaging the circumferential ends of said door, the longitudinally swinging edge of said door having a portion abutting in a radial direction with a fixed 115 part of said cylinder whereby the danger of egress of small articles from within said cylinder is minimized.

10. In a washing machine, a casing, a rotary cylinder mounted within said casing 120

and having small clearance relative thereto, said cylinder having a swinging door hinged about an axis parallel with the axis of said cylinder, said swinging door being provided with hinge and latch trimmings, said door and trimmings all being located within the circumferential contour of said cylinder, said latch trimmings including a latch,

and a circumferential band upon said cylinder, said latch being adapted to underlie ¹⁰ said circumferential band for locking purposes.

Signed at Moline, Illinois, this 30th day of January, 1923.

FRITZ BALZER.
